United States Patent Office.

JOHN CHRISTIANSEN, OF NEW YORK, N. Y., ASSIGNOR TO HIMSELF AND
B. KREISCHER, OF SAME PLACE.

Letters Patent No. 78,927, dated June 16, 1868.

IMPROVED HOISTING-APPARATUS.

The Schedule referred to in these Letters Patent and making part of the same.

TO ALL WHOM IT MAY CONCERN:

Be it known that I, JOHN CHRISTIANSEN, of the city, county, and State of New York, have invented a new and improved Hoisting-Apparatus; and I do hereby declare the following to be a full, clear, and exact description thereof, which will enable those skilled in the art to make and use the same, reference being had to the accompanying drawing forming part of this specification, in which drawing—

Figure 1 represents a transverse section of this invention, taken in the plane indicated by the line xx , fig. 2.

Figure 2 is a longitudinal section thereof, the line yy , fig. 1, indicating the plane of section.

Similar letters indicate corresponding parts.

This invention relates to an improvement in that class of hoisting-apparatus, the effect of which depends upon two or more differential gears.

The invention consists in a double-armed lever, placed loosely on the driving-shaft of the hoisting-apparatus, and carrying two pinions, which mesh into gears mounted firmly on said driving-shaft, and one of which also meshes into a stationary internal gear, while the other meshes into cogs on the inner surface of the drum, to which the hoisting-rope is attached, said pinions and gears being so adjusted in relation to each other that the gears mounted on the shaft have an equal number of cogs, while the number of cogs of the stationary internal gear is different from that of the number of the cogs of the internal gear in the drum, and the number of the cogs of one pinion different from the number of cogs of the other pinions, (or the number of cogs of the internal gear may be the same, and that of the other gears different, or the number of cogs on both pinions may be the same, and that of the internal gears and of the gears on the driving-shaft different,) in such a manner that by the combination of said double-armed lever and gears with the drum, a powerful hoisting-apparatus is produced. The invention consists, also, in the arrangement of a stationary rim and a series of friction-rollers, in combination with one end of the hoisting-drum, the opposite end of which is supported on the driving-shaft, in such a manner that a firm and durable bearing for said drum is obtained with the least possible friction.

A represents the driving-shaft of my hoisting-apparatus, which has its bearings in standards, B B', secured to a bed-plate or base, C, of any suitable nature. On this shaft are firmly mounted two gears, $a a'$, one of which gears into a pinion, b , and the other into a pinion, b' , and these pinions turn loosely on studs, $c c'$, which are firmly secured in a double-armed lever, D. Said lever turns loosely on the shaft A, and its arms may be made to extend in opposite directions from the centre of the shaft, or they may be at right angles, or at any other desirable angle towards each other.

The pinion b also gears into a stationary internal gear, d , which is rigidly connected to the standard B, and the pinion b' gears into an internal gear, d' , formed on the inner surface of the hoisting-drum E.

This drum has its bearings at one end on the shaft A, and at the opposite end on a series of friction-rollers, e, which roll on a rim, f, projecting from the standard B, so that both ends of said drums are well supported, and the friction between the working parts is reduced as much as possible.

In turning the shaft A by hand or other power, the pinions $b b'$ revolve around the gears $a a'$, and if the proportion between the gears $a b d$ is the same as that between the gears $a' b' d'$, the hoisting-drum remains stationary; but if these proportions are different, so that the motion of the lever D, due to the pinion b , is different from that which would be due to the pinion b' , the hoisting-drum necessarily must turn enough to make up for this difference, and a powerful hoisting-effect is obtained.

It is obvious that in this arrangement the gears $a a'$ may be alike, and the pinions $b b'$ and internal gears $d d'$ different in size, or the gears $a a'$ and pinions $b b'$ may be different, and the internal gears $d d'$ alike, or the gears $a a'$ and internal gears $d d'$ may be different, and the pinions $b b'$ alike, or all the gears may be different from each other without changing the effect, provided the proportion between the gears $a b d$ retains its relation to the proportion between the gears $a' b' d'$ unchanged.

Having thus described my invention, what I claim as new, and desire to secure by Letters Patent, is—

1. The combination of the lever D, carrying the pinions $b b'$, with the shaft A, gears $a a'$; internal gears $d d'$, stationary rim f, and drum E', substantially as and for the purpose described.

2. The combination of the stationary rim f supporting the friction-rollers e, with the hoisting-drum E, substantially as and for the purpose set forth.

JOHN CHRISTIANSEN.
